Patented Jan. 27, 1914.

UNITED STATES PATENT OFFICE.

DAVID ERIT, OF WESTPORT, NEW YORK.

CARBONATOR.

1,085,554.

Specification of Letters Patent.

Patented Jan. 27, 1914.

Application filed January 10, 1913. Serial No. 741,217.

To all whom it may concern:

Be it known that I, DAVID ERIT, a citizen of the United States, and a resident of Westport, in the county of Essex and State 5 of New York, have invented a new and Improved Carbonator, of which the following is a full, clear, and exact description.

This invention relates to an apparatus for carbonating and dispensing beverages, and 10 has for its object an inexpensive, simple, compact and reliable device for producing a rapid and perfect saturation of the liquid with carbon-dioxid. The carbon-dioxid and water are forced to pass together through 15 a continuous passage provided with a plurality of perforated and whirl-forming diaphragms toward the dispensing nozzle.

The invention consists of the construction and combination of parts to be more fully 20 described hereinafter and fully set forth in the claims.

Reference is to be had to the accompanying drawings forming a part of this specification, in which like characters indicate 25 corresponding parts in all the views and in which:

Figure 1 is an elevated longitudinal section through the member having the continuous passage; Fig. 2 is a section on line 2—2, Fig. 1; Fig. 3 is a plan view of a diaphragm provided in the continuous passage; and Fig. 4 is a section on the line 4—4, Fig. 3.

Referring to the drawings, 10 represents 5 a casing or member having a continuous passage. The continuous passage is formed of a series of horizontal superposed passages 11 interconnected alternately by means of vertical passages 12 angular in shape, so that the liquid passing from one horizontal 10 passage to the following one has not a smooth curved passage but an angular one, thus increasing the resistance to the passage of the liquid and forcing it to partly break up by expanding the same.

The casing 10 is provided with an inlet head 13 positioned on the upper end of the casing at the beginning of the continuous passage of the casing. The head 13 is at one side provided with superposed inlets of water and gas, 14 and 15 respectively. The pipe 16, leading the water to the inlet 14, is placed above the pipe 17 leading the gas to the inlet 15 of the head 13. Check valves 18

and 19 are provided on the pipes 16 and 17, allowing only the water and gas to flow inward into the head 13, but preventing the reverse.

The inlet proper of the continuous passage 11 formed in the head 13 is provided with an inverted, cup-shaped diaphragm 20 55 projecting with the bulged portion into the head 13. The diaphragm is provided with perforations 37 in its bulged portion projecting into the head, and also provided with radial slits 38 converging toward the center of the diaphragm, so that the water and gas enter through the pipes 16 and 17 into the head, are forced to pass through the perforations of the diaphragm and through the slits and, due to the construction of the slits the liquid is made to whirl 65 in entering the continuous passage 11.

Due to the superposed passage of the inlets of water and gas the film of water formed above the gas naturally tends to 75 flow downward, while the gas tends to rise, and, similarly, the water and gas being thrown against the walls of the head 13 and across the perforations and the slits of the diaphragm breaks up into finely divided 80 streams having an enlarged surface for contact with the gas present in the head coming through the inlet pipe 17. Under the pressure of the inflow water and gas the water passing through the diaphragm 20 flows into the passage and also rotates, due 85 to the creation of the whirl of the slits formed in the diaphragm 20.

The water flowing through the passages 11 coming in contact with the vertical passages 12, as above stated, again breaks up 90 and allows a better intermingling between the gas and the water present in the passage. That is, the area of contact of the liquid and the gas present is increased in 95 those vertical passages, thus allowing a better contact and, consequently, a better saturation of the water with the gas present. To form a better intermingling and create a continuous rotation of the flowing water, the passages 11 are provided with diaphragms 21 provided with perforations 39 and positioned near the opposite ends of the consecutive horizontal passages. The diaphragms 21 are also provided with radial slits 40 converging toward each other and 100 angularly disposed so as to create a whirl 105

when the water is passed through the slits. Again, due to the passage of the water through the perforations and slits, the water is divided into fine streams, thereby forming a large area exposed to the contact of the gas present, and, consequently, permitting a good saturation of the flowing water with the gas present in the passage. The number of passages provided on the diaphragms and the number of vertical connections 12 may be increased or decreased according to the size and the degree of saturation desired. The outlet of the casing 10, provided at the end of the continuous passage, is connected to a storage tank 22 in which the water saturated with the carbon-dioxide is stored and from where it can be drawn through the pipe 23 leading to the dispensing nozzles. The storage tank 22 is also provided with a pipe 24 leading to a pressure gage 25 indicating the pressure in the storage tank and from which it can be seen if the pressure should be increased or decreased. The casing 10 is also provided with a valve 26, positioned on one of the vertical passage members 12, for permitting the blowing out of the accumulated gas in the continuous passage of the casing.

When the carbon-dioxide and water flow through pipes 16 and 17 into the head 13, the water, flowing above the gas and being thrown against the wall of the head 13 and the cup-shaped diaphragm 20, breaks up and intermingles with the inflowing gas, and then, due to the perforation provided in the diaphragm, and also the radial curved slits in the diaphragm, the water is forced to whirl and break up into fine streams, thereby exposing a large surface to the contact of the gas present and similarly flowing through the passage. And, again, as above described, by this continuous division of water and gas into fine streams by means of diaphragms provided in the continuous passage, a large area of the flowing liquid is continuously exposed to the gas present and thereby a perfect saturation of the liquid and gas is obtained. The saturated liquid accumulated in the storage-tank from which it is dispensed by means of the pipes 23 may accumulate on the upper portion a certain amount of carbon-dioxide, particularly when the pressure is reduced, and, consequently, if the pressure is increased as we assume that the temperature remains constant this accumulated carbon-dioxide will necessarily dissolve when the pressure is reached which it had originally; also, the excess of carbon-dioxide accumulated in the top of the storage tank may be disposed of by means of a cock provided in the pipe 24, not shown in the drawing.

While the drawing shows the casing 10 cast in a single piece, the same may be

formed of a series of pipes soldered or otherwise secured to the vertical passages 12 similarly made of separate pieces or formed of a single piece with the pipes soldered to it. Diaphragms may be secured in the passage 11 by means of solder or any other suitable way. The angularity of the blades forming the diaphragm may vary, and the size of the slit formed between may also vary accordingly. The slits may be curved, as shown in Fig. 2, or straight as shown in Fig. 3, according to the amount of whirl it is desired to create in the continuous passage of the member 10. It may also be remarked that the diaphragms positioned in the passage create behind this passage a slight depression, thereby allowing an expansion of the liquid passing through the diaphragm and, consequently, obtaining a perfect intermingling of the gas and water by exposing much surface to contact.

Having thus described my invention, what I claim and desire to secure by Letters Patent is:

1. In a carbonator, a casing having a continuous angular passage therein for increasing the resistance to the flow of liquid through the same; a cup-shaped, perforated diaphragm at one end of said passage; an admission head over said diaphragm on said member having a water and a gas inlet therein, said diaphragm having its bulging portion projecting into said head, said angular passage having a plurality of fan-shaped, perforated diaphragms between its ends, and a storage tank associated with the end of said continuous passage opposite the one provided with the cup-shaped diaphragm.

2. In a carbonator, a casing having a continuous passage therein; a cup-shaped perforated diaphragm at one end of said passage; an admission head to said passage covering said diaphragm and having a liquid inlet and a gas inlet on the side thereof, said liquid inlet superposing said gas inlet, whereby gravity causes the liquid to cross the inflowing gas, said cup-shaped diaphragm projecting into said admission head with its bulging portion and having a plurality of curved slits converging toward the center.

3. In a carbonator, a casing comprising a series of superposed tubular members; angular portions connecting the ends of the adjacent tubular members so as to form a continuous passage, the said angular portions being of such a shape as to cause the liquid passing through the same to expand, and also to increase the resistance of flow of liquid through the same; a cup-shaped, perforated diaphragm having radial slits therein adjacent one end of said passage; an admission head over said diaphragm secured to said casing, said admission head

having a water and a gas inlet, said water inlet superposing said gas inlet, each adapted to supply transversely of said diaphragm; and a circular, perforated diaphragm having radial slits therein in each of said tubular members for the purpose set forth.

In testimony whereof I have signed my name to this specification in the presence of two subscribing witnesses.

DAVID ERIT.
